UNITED STATES PATENT OFFICE.

CHARLES F. FELTZ, OF ST. LOUIS, MISSOURI, ASSIGNOR OF ONE-FOURTH TO WILLIAM E. ANDERSON, ONE-FOURTH TO WILLIAM H. LANGDALE, AND ONE-FOURTH TO STONAY L. LANGDALE, ALL OF ST. LOUIS, MISSOURI.

BREATHER FOR INTERNAL-COMBUSTION ENGINES.

1,306,421.

Specification of Letters Patent. Patented June 10, 1919.

Application filed March 30, 1916. Serial No. 87,687.

To all whom it may concern:

Be it known that I, CHARLES F. FELTZ, a citizen of the United States of America, a resident of the city of St. Louis, State of Missouri, have invented certain new and useful Improvements in Breathers for Internal-Combustion Engines, of which the following is a full, clear, and exact description, reference being had to the accompanying drawing, forming a part of this specification.

My invention relates to improvements in breathers for engine crank cases. One of the objects is to produce a simple and inexpensive breather through which air may flow freely in one direction, the new breather being adapted to be secured to the crank case of an internal combustion engine so as to provide for the flow of air to and from the crank case in response to movements of the engine pistons.

A well known type of the internal combustion engine breathers now in use is in the form of a tube provided with deflector wings which extend downwardly from the inner face of the tube for the purpose of preventing the escape of oil with the outgoing air. The deflector wings of this prior device are inclined downwardly and their lower edges lie in a plane near the center of the breather tube. When the device is in service, some of the oil collects on the inner face of the tube and flows downwardly on the inclined wings and tends to drop from their lower edges at a point near the center of the tube. However, the outgoing air, rushing rapidly along these edges, tends to force the oil upwardly, so the drops of oil at said edges are atomized, reduced to a fine spray and carried upwardly with the air instead of being permitted to return freely to the crank case. The oil laden air escapes from the upper end of the breather tube with the result of wasting oil by depositing it at points that should be free from oil.

Therefore, a most important object of the invention is to produce an engine breather of the general type referred to above, but which is so constructed that the oil will 50 turn freely to the crank case, instead of being atomized and carried from the breather with the air. With this object in view the preferred form of the invention comprises a breather tube open at both ends to permit

the flow of air therethrough. Inclined deflector wings, extending upwardly from the inner face of the tube, form a series of oil-receiving pockets, the latter being open at the top to receive the oil. The oil accumulating on the inner face of the breather tube and on the bottom faces of the deflector wings, flows downwardly along the inner face of the tube and into the open upper ends of the pockets. Instead of tending to drop from the deflector wings at the center of the tube, the oil tends to accumulate in the pockets and each pocket is provided with a discharge port near its lower end so that the oil will flow by gravity along the inner face of the tube, pass from one pocket to another, and finally return to the crank case. The pressure of the outgoing air opposes the downward flow of the oil, and the oil usually accumulates in the pockets until the downward pressure, due to the weight of the oil, is sufficient to overcome the resistance of the air. The returning oil then flows in streams, instead of drop by drop, and since this oil flows along the inner face of the tube instead of along the deflector wings, it will readily return to the crank case.

Figure I is a front elevation of an internal combustion engine, equipped with a breather embodying the features of the invention.

Fig. II is an enlarged vertical section, showing the breather and a portion of the crank case.

Fig. III is a horizontal section on line III—III, Fig. II.

The internal combustion engine shown in Fig. I may have any desired number of cylinders A. B designates a crank shaft mounted in the crank case C.

To illustrate the preferred form of the invention, I have shown a breather tube 1, secured at its lower end to a wall of the crank case by means of screws 2. The breather tube extends upwardly from the crank case, and it is open at both ends to allow the air to flow freely from the port 3 in the crank case to an air deflector E at the upper end of the tube. The deflector I have shown comprises a cap 4 integrally connected to the threaded ring 5 through the medium of ribs 6. The ring 5 is screwed onto the upper end of the breather tube 1.

7 designates a screen surrounding the ribs 6 to prevent dust, etc., from entering the breather tube.

Two oppositely disposed rows of inclined 5 deflector wings 8, in the form of segmental webs, extend inwardly and upwardly from opposite sides of the inner face of the breather tube 1, so as to form two oppositely disposed rows of oil-receiving pockets 10 9, each of said pockets being open at the top to receive the oil. Each pocket 9 is provided, at the lower end, with a discharge port 10 for the discharge of oil at a point adjacent to the inner face of the breather 15 tube. The pockets 9 of each row are preferably in different horizontal planes, and in alinement with each other, so the oil may flow freely from the upper pocket of a row, along the inner face of the breather 20 tube, and through all of the other pockets of the same row. The oil carried upwardly by the outgoing air will collect on the deflector wings 8 and on the inner face of the tube at points where it is not subjected to the 25 entire force of the air current, and then flow downwardly into the pockets 9. It is also important to observe that the alternating inclined deflector wings are widely separated from each other to provide open 30 spaces above the upper edges of the oil receiving pockets; the upper edge of each pocket, excepting the highest pocket, being below the upwardly inclined bottom face of the next higher deflector wing, so that the 35 outgoing oil passing from said upwardly inclined bottom face will be discharged onto the walls of the open space above the oil receiving pocket.

In actual practice, I have found that the 40 oil will accumulate in the different pockets 9, the greatest quantity being present in the lowermost pocket while only a very small quantity reaches the uppermost pocket. The downward pressure, due to the weight 45 of the oil in the pockets, eventually becomes great enough to cause the oil to flow downwardly through the discharge ports 10, instead of dropping from the edges of the deflector wings, where it would be atomized 50 and carried away in the spray. The oil flows downwardly along the inner face of the breather tube and finally passes freely into the crank case in the form of a stream.

Each inclined deflector wing 8 preferably 55 extends from one side of the breather tube to a point beyond the center of said tube so that the end portions of the different wings will lie in the same vertical plane, thus preventing the air from rushing upwardly in a straight path at the center of the tube.

I claim:—

1. An engine having a crank case, a breather tube extending upwardly from and 65 in communication with said crank case,

and deflectors comprising oppositely disposed alternating segmental deflector wings extending upwardly from the inner face of said breather tube to provide oppositely disposed alternating oil-receiving pockets, 70 said upwardly extending alternating deflector wings being separated from each other to provide open spaces above the upper edges of the oil-receiving pockets and between the separated deflector wings; the 75 upper edge of each oil-receiving pocket, excepting the highest pocket, being below the upwardly extending bottom face of the next higher deflector wing so that the outgoing oil passing from said upwardly extending 80 bottom face will be discharged onto the walls of the open space above the oil-receiving pocket, said oil-receiving pockets being open at the top to receive the oil, and each of said pockets having a discharge port at 85 the bottom for the discharge of the oil.

2. An engine having a crank case, a breather tube extending upwardly from and in communication with said crank case, and deflectors in the form of oppositely disposed 90 wings extending upwardly from opposite sides of the inner face of said breather tube to form oil-receiving pockets, the deflector wings being separated from each other to provide open spaces above the upper edges 95 of the oil-receiving pockets; each deflector wing, excepting the wing at the bottom, being extended into the open space above the upper edge of an oppositely disposed oil-receiving pocket, so as to deflect the outgoing oil onto the walls of said open space above the oil-receiving pocket, thereby delivering the oil from the deflector wings on one side to the walls directly above oil-receiving pockets on the opposite side, said 105 pockets being open at the top to receive the oil, each of said pockets having a discharge port near its lower end and the pockets on each side being arranged in alinement with each other and in different horizontal planes 110 so that the oil passing from the discharge port of one pocket will flow downwardly by gravity into the next adjacent pocket and finally pass from the lower end of said breather tube to the crank case. 115

3. An engine having a crank case, a breather tube extending upwardly from and in communication with said crank case, said breather tube being open at its upper and lower ends to permit the flow of air therethrough, and two oppositely disposed rows of deflector wings extending inwardly and upwardly from opposite sides of the inner face of said breather tube so as to form two oppositely disposed rows of oil-receiving 120 pockets, the deflector wings being separated from each other to provide open spaces above the upper edges of the oil-receiving pockets; each deflector wing, excepting the wing at the bottom, being extended into the 125 open space above the upper edges of the oil-receiving pockets; each deflector wing, excepting the wing at the bottom, being extended into the 130

open space above the upper edge of an oppositely disposed oil-receiving pocket, so as to deflect the oil onto the walls of said open space above the oil-receiving pocket, there-
5 by delivering the oil from the deflector wings on one side to the walls directly above oil-receiving pockets on the opposite side, each of said pockets being open at the top to receive the oil and provided with a
10 discharge port at its lower end, the pockets of each row being formed in alternating relation to the pockets of the other row, and said pockets being in different horizontal planes so that the oil passing into the pocket
15 at the top of a row will flow downwardly, by gravity, along the inner face of said breather tube, through the lower pockets of the same row and finally pass from the lower end of said breather tube to the crank
20 case.

4. As a new article of manufacture, an internal combustion engine breather comprising a breather tube adapted to be attached at its lower end to the crank case of
25 an internal combustion engine, said breather tube being open at its upper and lower ends to permit the flow of oil-laden air there-
through, an air deflector at the upper end of said breather tube, and two oppositely dis-
30 posed rows of inclined segmental deflector wings extending inwardly and upwardly from opposite sides of the inner face of said

breather tube to points beyond the vertical center line of the tube so as to form two oppositely disposed rows of alternating oil-
35 collecting pockets, the segmental deflector wings of each row being widely separated from each other to provide open spaces above the upper edges of the oil-collecting pockets and between the separated deflector 40 wings, the deflector wings of each row, ex-
cepting the wing at the bottom, being ex-
tended into said open spaces and extended over the oil-receiving pockets of the oppo-
site row, so as to deflect the outgoing oil 45 onto the walls of said open spaces, thereby delivering the oil from the deflector wings of one row to the walls directly above the oil-collecting pockets in the other row, each of said oil-collecting pockets being open at 50 the top to receive the oil and provided with a discharge port at its lower end for the discharge of oil, each discharge port being formed near the inner face of said breather tube so that the oil passing through the dis-
55 charge ports will flow downwardly along said inner face, and the pockets of each row being formed one above the other so that the oil flowing downwardly from an upper pocket will flow through all of the 60 lower pockets of the same row and finally escape from the lower end of said breather tube.

CHARLES F. FELTZ.
